UNITED STATES PATENT OFFICE

WAYNE P. ZENT, OF TROY, NEW YORK

RAILWAY GATE

Application filed January 6, 1928. Serial No. 244,874.

This invention relates to improvements in automatic railroad gates, and is especially useful at highway crossings.

The automatic lowering of the common railway gate is in itself dangerous by its liability to trap a person or vehicle at the crossing. My object is to provide means whereby the highway crossing can be closed to traffic at the appropriate times and without danger to persons and vehicles at the crossing, and which is adapted to operate in connection with safety signal apparatus which I have described in a copending application Serial 259,536 filed March 6, 1928.

With the foregoing and such other objects in view as may be more fully described in the following specification, I have invented the device illustrated in the accompanying drawings, in which—

Figure 1 is a top plan view of a pair of gates, a system of solenoid gate-closing control devices, warning signals and wiring diagram associated therewith;

Fig. 2 is an elevation looking in the direction of the arrow in Fig. 1;

Fig. 3 is a vertical section taken on the line 10—10 of Fig. 1;

Fig. 4 is a plan view of a portion of a single thoroughfare crossing gate sweep showing the flexible means;

Fig. 5 is a side elevation of the structure shown in Fig. 4;

Fig. 6 is a plan view enlarged of one of the gates illustrating the wiring associated therewith; and

Fig. 7 is a side elevation of same.

Like reference characters designate like parts in the several views.

Referring to the accompanying drawings, the element designated 1 represents the rails of a railway line acting as an electrical conductor for the circuit employed in this invention. Any suitable source of current supply may be provided such as a dynamo, transformer or storage battery, and a conventional third rail 44 may be the electrical conductor.

In Figs. 1 to 5 inclusive are shown means for operating the crossing gates 47, which

are of the swivel type, being disposed transversely of and closing the railway tracks 1 when in their normal position, and swinging in a horizontal plane to close the highway crossing 50 when operated by a train entering crossing block.

The gate operating mechanism is suitably mounted in a metal container and installed in pairs, or otherwise, to meet the various conditions of highways crossing railways. The gate sweep rails 47 are suitably insulated and are pivoted at 48, as shown in Figs. 1 and 3 of the drawings, to turn on the pinion bearing 49. Pivot elements 48, 49 will be spaced from each other to correspond to the difference in width of the railway line as compared with the width of the highway 50 and overlapping when closing the narrower traffic route.

Stops 51, as shown in Fig. 6, are arranged to limit the outward throw or travel of the gates; and stops 52 to limit the inward throw, the latter being threaded to permit of adjustment.

The gate sweep rails 47 are provided with electrical spring contacts 54 and 54a which engage with members 51 and 51a. Members 51 and 51a also will act as electrical contactors and are multiple connected at 53. The gate sweep rails 47 are provided with electric lamps 55. Movement of gate sweep 47 is by means of solenoid 60, and it is automatically returned by gravity to normal position by weight 61.

An arc or sheave 62 is mounted to the top of the sweep 47. A flexible connector or cable 66 is attached to the sheave 62 as shown in Figs. 1 and 2, and passes around the sheave or pulley 64 and terminates in a connection to the magnetic draw bar or pin 65. This draw bar has free passage through the gate frame and has a magnetic core end 65a faced toward the magnetic core end 60a of the solenoid 60 which is mounted and secured on the gate frame in line with the draw bar 65. Another flexible connector or cable is attached to the sweep 47 as shown in the drawings at 67 and passes through the pulleys 68 and 68a and terminates in its attachment to the weight 61.

Normally, when the gate sweep is across the track 1 the weight 61 is at its lowest level and the magnetic cores 60a and 65a are separated, there being no magnetic influence exerted by the solenoid 60. When the solenoid 60 is energized it exerts its electrical influence on its magnetic core 60a which in turn draws the magnetic core end 65a and its integral draw bar 65 to it and 10 the cable 63 is drawn by the draw bar and uncoiled from drum or sheave 62, thereby turning the disc to swing the gate sweep 47 on its bearing 48, separating its electrical contactor 54 from engagement with 15 the gate stop electrical contactors 52 and 52a until it is stopped by contact of its other electrical spring contactor 54a engaging with the gate stop contactors 52 and 52a to be held thereto by the electrical force of the 20 solenoid upon the draw bar core. When, under predetermined conditions, the solenoid circuit is broken, the operation of the weight 61 by gravity will effect the return of the gate sweep 47 to its normal position 25 across the track, with the sweep 47 and electrical contactor 54 again in contact with the gate stop electrical contactors 52 and 52a.

Referring to Fig. 2, attached to the drum 30 or sheave 62 mounted around the pinion 49 is a flexible connector or cable 63 running through pulley 64 to a draw pin 65 slidable through gate frame to engage with solenoid 60. Another flexible connector or cable 66 35 is attached to the gate sweep 47 at 67 and runs through pulleys 68 and 68a to a weight 61.

As shown in Fig. 4, the sweep rails 47 are pivoted at 69 with spring hinges 70 and 40 buffer stops 71, and provide flexibility to the sweep rail 47 when held against the stop post 59, as shown in Fig. 1, it being obvious that the rail 47 can be forced toward the solenoid 60 by undue pressure. Figs. 4 and 45 5 also show that in this application the connectors 54 and 54a are slidably connected. Although these figures show means for flexible horizontal movement, I do not wish to be restricted thereto, as similar 50 means can be applied vertically to allow gates to be raised to a vertical position in case such operation is desired.

The gate sweep rails 47 are suitably parted 55 semaphore like, or may bear a suitable warning stop sign, thereby providing additional safety means.

The ground clearance of gate sweep 47 is 60 within the limit to strike not higher than the middle of an ordinary automobile radiator, so that no personal injury and a minimum of property damage would follow a disregard of the danger warning given in advance of the gates closing the highway, and it is possible to secure an elimi-

nation of any damage by equipping gate sweep rails 47 with pneumatic bumpers.

Certain gate mechanism containers are extended vertically as shown at 72, bearing lamps and bell crossing signal units 73 and 73a, faced directional to right hand flow of 70 highway traffic.

Extending a suitable distance each side of the highway crossing and parallel with the railway tracks are the side rails 75 and 75a, as shown in Fig. 3, the rail 75 being extended beyond each end of the rail 75a. These rails provide connector means for crossing signals, gate operation, cab signals 75 and automatic train stop. Member 75 is a casing for members 75 and 75a, casing 45 being supported by bracket 46.

From the side rail 75a electrical connection is made through all the solenoids 60 employed at a certain crossing and grounded to track rail 1, making the circuit from side rail 75a to track rail 1. This leaves the several gate and signal circuits at each crossing open at the side rails 75 and 75a and track rail 1.

The action of the solenoid 60 is almost instant. The sweep of the gate rails 47 covers the entire extent of the crossing area and should there be any obstruction therein preventing the gates from fully closing, the 95 spring contactors 54 and 54a on the gate sweep rail 47 would fail to engage the gate stops 52 and 52a, thereby leaving the circuit closed and giving warning that the track was not clear ahead. Should the obstruction be temporary at the instant of its removal the gates would fully close the highway allowing the train to proceed without danger.

Connector rails are supported at the crossing so as not to obstruct same and the electrical connections between the rails are run beneath the surface of the highway at the crossing.

The invention may be applied to third rail electric railways or other types of railways in common use.

I have shown the invention in preferred form as used with swivel gates, but do not wish to be restricted thereto, as swivel gates stationed parallel with highway in normal position, common horizontal gates in common position, and gates beneath highway surface in normal position, can be used in combination with my train crossing signal and automatic train stop. Neither am I restricted to the use of side rail connector, as overhead wires or common track rails can be used.

I do not desire to be restricted to the use 125 of solenoids to operate the gate closing, as other common power means can be used in combination with the other safety features of this invention.

The electric current supply for crossing 130

signal and control and gate operation can be applied in the circuits at each crossing instead of in motor train as shown.

What I claim is:

- 5 In combination, a gate pivoted upon a vertical axis, a sheave carried with the gate, flexible member fixed to the sheave, and adapted to ride on the sheave, and solenoid means connected with the flexible member
- 10 and a second sheave and a second flexible member connected with the second sheave, and a weight connected to the second flexible member.

In testimony whereof I affix my signature.

WAYNE P. ZENT.
